METHOD OF MAKING CATHODES

William W. Eitel, Salt Lake City, Utah, and Jack A. McCullough, Millbrae, Calif., assignors to Eitel-McCullough, Inc., San Bruno, Calif., a corporation of California

Application August 24, 1942, Serial No. 456,127

4 Claims. (Cl. 140—71.6)

1

Our invention relates to the manufacture of cathode structures for electronic tubes.

It is among the objects of our invention to provide a method of making a helical-type filamentary cathode, whereby distortion of the filament during welding is largely eliminated.

Another object is to provide an improved method of welding a filament to a lead, producing a clean weld having superior mechanical strength.

The invention possesses other objects and features of advantage, some of which, with the foregoing, will be set forth in the following description of our invention. It is to be understood that we do not limit ourselves to this disclosure of species of our invention, as we may adopt variant embodiments thereof within the scope of the claims.

Referring to the drawing:

Figure 1 is an exploded elevational view showing a filament and associated parts prior to engagement of the upper welding disk.

Figure 2 is a plan view looking down at the top of the filament before applying the welding disk, illustrating the clearance between the end coil and lead prior to welding.

Figure 3 is a vertical sectional view showing the cathode structure within a bell jar ready for welding.

Figure 4 is a side elevational view of the welded filament.

In terms of broad inclusion, our method of making a cathode structure comprises forming a helical filament with a reduced end coil sized to loosely encircle a lead, positioning the filament with the coil embracing the lead, fixing the other end of the filament, and then welding said coil to the lead. In making our structure we preferably first seal a pair of cathode leads to a stem; then fix the lower end of the filament by welding to one of the leads; and then weld the coil at the upper end of the filament to the other lead. Welding is preferably effected by an electric arc in an atmosphere of hydrogen, after which the structure is heated in a hydrogen atmosphere by passing current through the filament.

In greater detail, and referring to the drawing, we first fix a pair of leads 2 and 3 to a support, as by the usual practice of sealing them to a stem 4 of the envelope which encloses the cathode in the final tube. Short lead 3 is arranged to terminate adjacent the lower end of a helical filament 6, while longer lead 2 is disposed coaxially with the cathode to terminate adjacent the upper end of the filament, in accordance with ordinary prac-

2

tice of making filamentary cathodes of this character. Both leads are preferably of tungsten.

Helical filament 6, preferably of thoriated tungsten, is provided with a depending lower end 7 arranged to lie alongside lead 3 when the filament is centered about lead 2. The upper end of the filament is formed with a reduced coil 8 aligned with the axis and sized to loosely encircle the upper portions of coaxial lead 2. Three convolutions are shown in coil 8, but it is understood that one or more may be present in the coil, the important thing being that the convolutions are spaced from lead 2 to give freedom of movement to this end of the filament. See Figure 2.

15 The filament is temporarily held by a jig comprising a longitudinally split body having a pair of half-sections 9 gripped by jaws 11 of a suitable clamp, and having an axial bore through which the helical portion of the filament extends.

20 The diameter of the bore is preferably slightly larger than the outside diameter of the helix so that there is a small clearance, just enough to prevent binding of the parts and to allow some freedom of movement. The jig is centered by 25 spacing lugs 12 engaging coaxial lead 2 between the convolutions of the helix. These lugs also hold the filament in proper axial position. The free play at the top provided by the clearance between coil 8 and lead 2 allows the helix to be centered without putting stress in the wire, which stress would cause distortion after the jig was removed.

30 In assembling the parts, a tab 13 of metal flux is first spot welded to lead 3. Any suitable material, such as platinum, which fluxes or welds readily with both the filament and lead may be used. The filament is then mounted by the jig on center lead 2 with its depending end 7 against tab 13 on lead 3. Another piece of metal flux is 35 also applied to the junction between coil 8 and the center lead. This piece preferably comprises an apertured disk 14 of molybdenum engaged over the end of lead 2 above coil 8. The disk is thus held by the lead ready for welding and allows the structure to be elevated into a bell jar without the disk falling off.

40 The whole structure is then elevated into bell jar 16 containing an atmosphere devoid of oxygen. A hydrogen atmosphere is preferred, the gas being admitted through tube 17. A pair of arc welding electrodes 18 are sealed to the sides of the jar, to which suitable connections are made to furnish current from the arc. In the type of 45 cathode illustrated, the juncture at the lower end

3

of the filament is preferably first brought into the arc for welding. The heat causes piece 13 to flow or flux into intimate contact with the filament and lead, producing weld 19 shown in Figure 4.

One of the most difficult problems in mounting a helical filament is that the heat coincident with welding causes distortion of the filament. This distortion is largely eliminated in our procedure because the filament is free to turn under torque stresses set up in the helix due to expansion of the wire under heat. Loose coil 8 at the top permits the filament to rotate about lead 2 without destroying the coaxial alignment. After making weld 19 the structure is lowered to place the upper juncture in the arc. The molybdenum flows down over the convolutions of coil 8, filling the space between the coil and lead, and welding the parts together without altering the alignment of the filament. The final weld is a smooth bead 21 enveloping the coil as shown in Figure 4. Arc welding in a hydrogen atmosphere results in clean welds, free of oxides and other contamination which, if present, are difficult to eliminate and adversely affect the operation of a tube.

Upon completion of the upper weld the structure is withdrawn from the bell jar and the jig is removed. In order to further improve the welded joints we preferably again elevate the structure into a hydrogen filled bell jar and heat the cathode to incandescence by passing current through filament. This causes further knitting of the welding material and produces smooth, tight joints.

We claim:

1. The method of making a cathode structure, which comprises forming a helical filament with a reduced coil at one end sized to loosely encircle a lead, positioning the filament with said coil embracing the lead, welding the other end of the filament to another lead, applying to the juncture at said coil a piece of metal weldable with the filament and said first lead, and then subjecting the juncture to welding heat.

2. The method of making a cathode structure which comprises forming a helical filament with a reduced coil at its upper end sized to loosely encircle a first lead, positioning the filament with said coil embracing the lead and with its lower end adjacent another lead, welding the lower

end of the filament to said other lead, engaging over the upper end of the first lead an apertured piece of metal weldable with the filament and the first lead, and subjecting the juncture at the upper end of the filament to welding heat.

3. The method of making a cathode structure, which comprises fixing a pair of leads to a support, forming a helical filament with a reduced coil at its upper end sized to loosely encircle a first of said leads, positioning the filament with said coil embracing the first lead and with its lower end adjacent a second lead, welding the lower end to the second lead, and welding the coil to said first lead.

4. The method of making a cathode structure, which comprises fixing a pair of leads to a support, forming a helical filament with one end portion directed toward the helical axis so as to lie in close proximity to such axis, positioning a first lead of said pair within the helix of the filament in substantial alignment with the helical axis thereof and contiguous to the inwardly directed end portion of the filament, positioning the second lead of said pair adjacent the opposite end portion of said filament, welding said last named end portion of said filament to the adjacent second lead, and thereafter welding said first named end portion of said filament to said first lead.
